CLAIM

The ornamental design for an exhaust vent cover for water heater, as shown and described.

DESCRIPTION

FIG. 1 is a front perspective view of an exhaust vent cover for water heater showing our new design;
FIG. 2 is a rear perspective view thereof;
FIG. 3 is a front view thereof;
FIG. 4 is a rear view thereof;
FIG. 5 is a top plan view thereof;
FIG. 6 is a bottom plan view thereof;
FIG. 7 is a right side view thereof;
FIG. 8 is a cross-sectional view taken along line 8-8 in FIG. 3 thereof;
FIG. 9 is a cross-sectional view taken along line 9-9 in FIG. 3 thereof;
FIG. 10 is a cross-sectional view taken along line 10-10 in FIG. 3 thereof; and,
FIG. 11 is a front perspective view showing the article in use.

The evenly-spaced broken lines illustrate portions of the exhaust vent cover for water heater that form no part of the claimed design. The dash-dotted broken lines denote the boundary of the claim and form no part of the claimed design.

1 Claim, 10 Drawing Sheets
